UNITED STATES PATENT OFFICE.

CHARLES WELLINGTON WALKER, OF BRIDGEPORT, CONNECTICUT,
ASSIGNOR TO YOST WRITING MACHINE COMPANY, OF ILION,
NEW YORK, A CORPORATION OF NEW YORK.

TYPE-WRITING MACHINE.

No. 841,288.

Specification of Letters Patent.

Patented Jan. 15, 1907.

Application filed December 21, 1901. Serial No. 86,821.

To all whom it may concern:

Be it known that I, CHARLES WELLINGTON WALKER, a citizen of the United States, and a resident of Bridgeport, in the county of 5 Fairfield and State of Connecticut, have invented certain new and useful Improvements in Type-Writing Machines, of which the following is a specification.

My present invention relates to type-writing machines; and the object of said invention is to improve various portions of the machine and to provide a construction in which many of the disadvantages of prior machines are overcome.

15 To these ends the invention consists in the novel features of construction and arrangements and combinations of parts, as herein-after described, and particularly pointed out in the appended claims.

20 In the accompanying drawings, wherein like reference characters represent corresponding parts in the various views, Figure 1 is a vertical sectional view of one form of type-writing machine embodying the invention, the section being taken from front to rear of the machine, with parts broken away and parts omitted to more clearly illustrate other portions of the structure. Fig. 2 is a detail side view of a portion of the carriage-

25 feed mechanism and the parts which connect it with the space-key, together with a portion of the line-lock mechanism. Fig. 3 is a detail plan view of a portion of the carriage-feed mechanism. Fig. 4 is a like view of the same, but showing the stepping-dog in a disengaged position. Fig. 5 is a fragmentary detail perspective view of the carriage-release. Fig. 6 is a like view of the same, showing some of the parts in different positions.

30 Fig. 7 is a side view, partly in section, of the carriage-feed mechanism and a portion of the line-lock mechanism. Fig. 8 is a like view of the same, but showing the line-lock devices in an operative position. Fig. 9 is a detail plan view of parts of the line-lock mechanism.

35 Fig. 10 is a like view of the same in locking position. Fig. 11 is an enlarged detail vertical sectional view of a portion of the carriage-feed mechanism and of the line-lock mechanism. Fig. 12 is a detail perspective view of part of the carriage-feed mechanism. Figs. 13, 14, 15, and 16 are detail perspective views 40 of portions of the carriage-feed and line-lock

mechanisms. Fig. 17 is a detail face view of one of the clutches forming part of the carriage-feed mechanism. Fig. 18 is a detail perspective view of a portion of the line-lock mechanism. Fig. 19 is a fragmentary vertical section of a portion of the line-lock mechanism, the section being taken on the line *u u* 45 of Fig. 18. Figs. 20, 21, 22, 23, 24, and 25 are detail perspective views of portions connected with the carriage-feed mechanism. Figs. 26 and 27 are detail perspective and vertical sectional views, respectively, of portions of the line-lock mechanism. Fig. 28 is 50 a plan view of the carriage. Fig. 29 is a detail end view of the carriage, the view being taken in the direction of the arrow in Fig. 28. Fig. 30 is a transverse sectional view taken 55 through the platen-frame at the left-hand end portion thereof. Fig. 31 is a detail perspective view of the means for connecting the platen-frame to the carriage. Figs. 32 and 33 are enlarged horizontal longitudinal section 60 detail views of the means for connecting the platen-frame to the carriage, the section being taken centrally of a locking-bolt.

In the various figures of the drawings parts have been omitted and other parts 65 broken away to more clearly illustrate other portions of the structure.

The improvements which constitute the subject-matter of the present invention are shown in their application to that type of 70 machines which is known as the "Yost" machine, though obviously some of the features of invention may be applied to any character of type-writing machines wherein they may be found available.

Referring now to the drawings, 1 indicates the frame of the machine, which supports a type-ring 2, provided with radial slots 3 for the reception of arms or drivers 4, each driver having a hook-like projection 5, 75 which bears upon a fulcrum-ring 6, arranged in a groove in the type-ring or support 2. One end of each driver is pivotally connected at 7 to a type bar or carrier 8. A guide-link 9 is pivotally connected at 10 to another portion of said type bar or carrier, and said guide-link is formed at its pivotal end with a disk-like portion 11, which is held in recesses or bearings formed by a pair of circular plates 12 and 13, suitably clamped together 80 and supported centrally of the type-bar sys-

tem. The faces of the types 14 on the various type-bars normally rest against an inking-pad 15, which is supported on the type-ring 2. The driver 4 of each type bar or carrier is provided with an extension 16, to which is connected at 16^a the upper end of a draw-link or pull-rod 17. The lower end of each draw-link 17 is operatively connected to a bell-crank lever 18, that is pivoted at 19 to a hanger 20, which in turn is secured between clamping-plates 21.

Each driver 4 and the draw-link 17 thereof is connected by a contractile spring 22 in order to restore the type-bar and its connected parts to their normal positions. Each bell-crank lever 18 has one arm thereof operatively connected at 23 to a draw-link 24, which has a general horizontal disposition and which is connected at its opposite end 25 to an actuating-lever 26, pivoted at 31 and connected by an arm 32 to a key-stem 34. Each key-stem may in a like manner be connected to a second guide-arm 36, pivoted at 39.

Above the circular supports 12 13 for the type-bars is arranged a circular universal bar 50, with which the guide-link 9 of each of the type-actions is adapted to contact in the movement of the type to the printing position. This contact of the guide-link with the universal bar 50 is sufficient to raise the latter at one side, as shown in Fig. 1 of the drawings. Depending centrally from the universal bar is a rod 51, which is provided with a head 52, and said rod passes loosely through a central aperture 53 (see Fig. 20) in the universal bar or the spider 54, forming a part thereof. This rod also passes through an aperture in a central hub 55^a, forming a part of the framework of the machine. (See Fig. 27.) This hub is provided with a threaded tubular neck 55^b, over which the supports 12 and 13 are slipped and then clamped on the shoulder of the hub by a nut 55^c, the supports 12 and 13 being formed with central apertures 55, Figs. 21 and 22, for the purpose of enabling them to be seated on said shoulder. Said rod 51 is threaded at its lower end and engages with the interiorly-threaded portion of a neck formed at the upper end of a block 56, to which is pivoted at 57 the forward end of a dog-rocker 58, that is pivotally supported upon a fixed bar 59, which extends from side to side of the frame and is secured at its ends thereto. The rocker is provided with a fixed or rigid dog 60 and a loose dog 61, the loose dog 61 being pivoted at 62 (see Figs. 3 and 4) and having a lateral extension 63, that carries a depending pin 64. This depending pin 64 is connected to one end of a coiled spring 65, the opposite end of which is secured to a pin 66, carried by the dog-rocker. The spring 65 tends normally to maintain the loose dog 61 in the position shown in Fig. 4, and the movement of

the dog by the spring is limited by a fixed pin 67.

The lower end of the block 56 is threaded interiorly, Fig. 27, to receive the upper threaded end of a rod or pin 51^a, which is provided at its lowermost end with a head or shoe 68, that co-operates with a rounded shoe 69, carried by a bell-crank lever 70, that is pivoted at 71 to an arm 72, which projects forwardly from a fixed rod 73, that extends across the machine and is supported by the sides of the frame 1 thereof. Connected to the vertical arm of the bell-crank 70 is a draw-link 74, which has its opposite end pivotally connected at 75 to a lever 76, that is pivotally supported upon the rod 77 and has a forwardly-projecting arm 78, which is pivotally united at 79 to a depending stem 80 of the space-bar 81. The stem 80 of the space-bar may be notched, as shown at 82, for the reception of a longitudinally-extending bar 83, which is connected to links or guide-arms 84, that are pivoted upon one of the rods 39, which extends from side to side of the machine. It will be observed that the space bar or key is supported and guided in its movements in a similar manner to the character-keys and so that the space-bar or the stem therefor has a substantially true vertical movement when operated. The motion transmitted to the parts by a depression of the space bar or key 81 is effective to raise the rod 51 without, however, transmitting movement to the universal bar by reason of the fact that the rod 51 projects loosely through the central opening 53 in the spider of the universal bar. A depression of the space-key will, through the lever 76, connecting-rod 74, bell-crank 70, and block 56, cause the dog-carrier 58 to vibrate on its pivot 59 and move the loose dog 61 down out of engagement with a tooth of the feed or escapement wheel 86 and bring the fixed dog 60 into engagement with said wheel, as shown in Figs. 2 and 4, and when the space-key is released the loose dog will again be brought into engagement with the next tooth of the feed-wheel, and the carriage will be advanced one letter-space distance, as will hereinafter more fully appear.

When the block 56 is actuated by the space-key to effect the rocker as just described, the free end of the rod 51 moves upwardly through the aperture in the universal bar or in the spider or armed portion thereof, and the universal bar remains at rest in its normal horizontal position, as shown in Fig. 2. When, however, a character-key is depressed, the universal bar will be acted upon on one side by the link 9 of the particular type-bar actuated, as shown at Fig. 1, and by the engagement of the spider with the head 52 of the rod (the diametrically opposite portion of the spider bearing on the plate 13 as a fulcrum) lifts the rod, and

the block and the dog-rocker will be vibrated to throw the loose or spacing dog out of engagement with the escapement-wheel and the rigid dog into engagement therewith. 5 When the depressed key is relieved of pressure, the parts are all restored to their normal positions by their several springs.

Upon reference to Figs. 11 and 12 it will be seen that the feed-wheel 86 is rigidly connected by a screw 87 to a hollow shaft 88, that is vertically disposed and extends through the base to the upper portion of the machine. This sleeve or hollow shaft 88 has secured thereto by a screw 89 a clutch-section 90, which is provided with peripheral ratchet-teeth 91 and with upwardly-extending ratchet-teeth 92. The ratchet-teeth 91 coöperate with a spring-pressed pawl 93, pivoted at 94 to the framing 1 of the machine, so that the clutch-section 90, the hollow shaft 88, and the feed-wheel 86 may rotate in but one direction, which is the direction of feed and is indicated by the arrow upon the feed-wheel in Fig. 12.

Coöperating with the upwardly-extending teeth 92 of the clutch-section 90 is a gravity-pawl 95, that is pivoted at 96 to a clutch-section 97, that bears at its lower end in a recess 98, Figs. 11 and 17, within the row of upwardly-extending teeth 92 on the clutch-section 90. The disposition of the pawl 95 is such that the clutch-sections 90 and 97 may rotate together when the feed-wheel and the clutch-section 90 connected thereto are moved in the direction of the arrow in Fig. 12. The upper edge of the clutch-section 97 is provided with teeth 99, that coöperate with teeth on a clutch-section 100, that is secured by a screw 101 to a hollow shaft 102, that surrounds the hollow shaft 88 for a portion of its length, and both of the hollow shafts project through and above the top plate or type-ring 2 of the machine. Surrounding the hollow shaft 102 is a coiled spring 104, which bears at its upper end against a cylindrical housing 105, that surrounds the spring and is rigidly connected to rotate with the clutch 97 by a screw 105^x. The other end of the spring 104 bears against the top of the clutch-section 100, and the expansion-spring normally maintains the teeth of the various clutch-sections in engagement. The hollow shaft 102 carries at its upper end a pinion 106, and just below the pinion 106 is secured a second pinion 107. Upon reference to Figs. 1, 5, 7, and 8 of the drawings it will be seen that the pinion 106 meshes with a feed-rack 108, that is carried by the carriage 109, whereas the pinion 107 meshes with a gear 110, that is connected to a pinion 111, which in turn meshes with a rack 112, that is carried by a ball-separator 113. This separator may be of any suitable construction and is adapted to maintain the loose anti-friction-balls 114 in a fixed relation one to

another in the fixed raceways 115 during the travel of the carriage from end to end of the machine. It will be understood that a rotation of the hollow shaft 102 will cause a rotation of the feed-pinion 106 and the pinion 107, so that the ball-separator and carriage will be moved when the escapement mechanism is operated to effect a rotation of the hollow shaft. It should be understood that a suitable spring-drum (not shown) is connected to the carriage to move it in the direction of its feed, or from right to left, when the escapement mechanism is operated, as in prior machines.

Secured to the carriage 109 and extending longitudinally thereof from end to end is a bar 116, Figs. 5 and 6, which extends beneath the pinion 106 and is provided at its ends with inclined slots 117, into which project pins 118, that are secured to the carriage. 80 The bar 116 is likewise provided with an upwardly-extending finger 119, that projects into an elongated slot 120 of a lever 121, that is pivoted at 122 to the carriage and has an arm 123, that coöperates with a lever 124, 90 pivoted at 125, Fig. 28, to the platen-frame 126. This lever 124 is provided at its forward end with a finger-key 127, and when the lever 123 is vibrated on its pivot through an actuation of the finger-piece 127 the bar 116 will be elevated by reason of the pin and inclined slot connection provided therefor. This upward movement of the bar 116 will cause the pinions 106 107 to be elevated, but not sufficiently to disengage them from their racks. A like elevation of the hollow shaft 102 is produced, which effects an upward movement of the clutch-section 100 carried thereby to disengage it from the coöperating clutch-section 97, (see Fig. 8,) when the carriage is then free to be moved in either direction. In this movement of the shaft 102 the spring 104 is compressed, and when the finger-key 127 is released the parts will be immediately restored to the normal or engaging position. (Shown in Fig. 7 of the drawings.) Should the carriage be moved from left to right without disengaging the clutch-sections by means of the hand-operated release-key 127, the clutch-section 100, the 115 spring 104, the cylindrical housing 105, which is secured to the clutch-section 97, and the clutch-section 97 will be rotated together without transmitting movement to the feed-wheel 86 or to the other clutch-sections, because at this time the pawl 95 on the clutch member 97 will ride freely over the teeth 92 on the clutch-section 90, and hence no movement will be transmitted to the clutch-section 90 or the escapement-wheel 86. When, 125 however, the carriage-driving spring (not shown) is rendered effective to move the carriage in the direction of its feed, or, in other words, when the escapement mechanism is operated, the tension of the carriage-spring 130

causes the hollow shaft 102 to be rotated through the rack-and-pinion connection between the carriage and the shaft 102, and by this movement the carriage will cause the clutch-section 100, the clutch-section 97, the coiled spring 104, the cylindrical housing 105, the clutch-section 90, and the feed-wheel 86 to be rotated, and in this movement of the parts the pawl 95 is effective to cause the clutch-sections 97 and 90 to rotate together. This movement of the carriage causes a rotation of the coiled spring 104 and the cylindrical housing therefor with the shaft 102 and the coöperating clutch-sections, and for this reason the tension of the spring 104 does not retard the movement of the carriage or the escapement mechanism, although it exerts a pressure to maintain the clutch-sections in operative engagement, and this construction constitutes a feature of the present invention.

Extending through the horizontally-disposed feed-wheel 86 and the vertically-disposed hollow shafts 88 and 102 is a shaft or rod 128, which is guided by but is freely movable within the hollow shaft 88. The upper end of this rod 128 has rigidly secured thereto an arm 129, to which is pivoted at 130 an abutment or stop 131. The downward movement of this abutment 131 is limited by a finger 132, Fig. 19, which projects from the arm 129, and this abutment 131 is normally maintained against the finger 132 by a spring 133, which bears at one end against the abutment and at its opposite end against the arm 129. The abutment 131 normally projects into the path of a coöperating abutment 134, that is beveled at 135 on the right-hand side thereof, as shown in Figs. 9 and 10, whereas the left-hand side of the abutment presents a square or vertical face, which co-operates with the abutment 131 to move it toward the left. The abutment 134 is carried by a sleeve 136, which is adjustable upon a rack 137, carried by the carriage. The lower end of the shaft 128 has an arm 138 rigidly secured thereto and projecting forwardly therefrom, and the forward or free end of this arm 138 carries a depending pin 139, which is adapted to project through an elongated opening or slot 140, Fig. 26, in a bell-crank line-lock lever 141, which is pivoted at 142 to the fixed bar 73, that extends from side to side of the machine. This bell-crank line-locking lever is maintained normally in the disengaged position by a contractile spring 144, Figs. 9 and 10, which is secured at one end to a pin 145 and at the other end at 146 to one arm of the locking lever. The terminal of the arm 147 of the line-locking lever is adapted to project above the shoe 68, that is operatively connected to the dog-rocker 58. The traveling abutment 134 is adjusted to the proper position on the rack 137 where it is desired to lock the print-

ing and feeding mechanisms against operation at the end of a line.

When the carriage is moved in the direction of its letter-feed, or from right to left, and the end of the line as determined by the adjustment of the abutment 134 is reached, said abutment will be brought into contact with the abutment 131 of the line-lock mechanism, and a slight further movement of the carriage will cause the abutment 131 to move therewith, thus turning the shaft 128 on its axis. This slight turning movement of the shaft 128 is effective to move the locking-lever 141 from the position shown at Fig. 9 to that illustrated in Fig. 10. When the locking-lever is in the position shown in Fig. 10, the shoe 68 is prevented from upward movement, so that the universal bar or ring 50, which is operatively connected thereto, and the dog-rocker 58, which is likewise operatively connected thereto, will be locked against movement by the finger-keys or space-bar, and at this time no further writing can take place. Should the operator desire to write one or more characters, to insert a hyphen, or complete a word, the abutment 131 may be moved out of the path of its coöperating abutment 134 to permit a further feed movement of the carriage and to release the line-lock. This is accomplished by the depression of a separate finger-key that is preferably located at the keyboard of the machine. This finger-key is connected and mounted in the same manner as the other finger-keys at the keyboard and is adapted to transmit motion through a draw-link 149 (see Figs. 1, 2, and 11) to a lever or cam 150, to which the draw-link is connected at 151. This lever or cam 150 extends beneath the lower end of the shaft 128, so that when the line-lock release-key is depressed the lever 150 will be moved around its pivot 152, thus causing the shaft 128 to be moved upwardly or in the direction of its length, as shown in Fig. 7 of the drawings. This movement of the shaft 128 carries with it the abutment 131, which at this time is raised to a position where it is out of the path of the coöperating abutment 134 on the carriage. As soon as the abutment 131 has been released from its coöperating abutment 134 in the manner described the tension of the spring 144 is effective to restore the line-lock lever 141 and the parts connected therewith to the normal or unlocking position represented in Fig. 9, and the printing and the spacing mechanisms may be operated as before to finish out the line. The abutment 134 having moved to the left of its coöperating abutment 131, it is necessary that the abutment 134 shall be able to freely pass the abutment 131 in the movement of the carriage from left to right. This is accomplished by the beveled face 135 upon the abutment 134, which on the return movement of the carriage to the right contacts

with the abutment 131 and moves it upwardly about its hinge-pin 130, and this permits the abutment 134 to pass under and by the abutment 131, the spring 133 serving to restore the abutment 131 to its normal position after it has been released by the abutment 134.

Referring particularly to Figs. 28, 29, 30, 31, 32, and 33 of the drawings, it will be seen that the platen-frame 126 carries rearwardly-projecting arms 153, which constitute bearings for the reception of movable locking-plungers 154, each of which is provided at its outer end with a hand-operated head 155, that is apertured for the reception of an expansion-spring 156, which bears against the head at one end and against the bottom or inner wall of a recessed portion 157, formed in an extension of the platen-frame pintle or hinge-pin, and which extension is fast or tight in the arm 153. The inner end of each of the locking-plungers 154 is provided with an enlarged portion or cylindrical locking-head 158, that is adapted to be seated in a circular recess 159 in an open bearing 160, that extends upwardly from the carriage 109. The platen-frame pintle or finger-pin 160^a turns in the open bearing 160 when the platen-frame is swung up to inspect or correct the work. The plunger 154 passes through said pintle and takes a bearing therein as well as in the extended portion of said pintle, which is fast in the arm 153. When the locking-head 158 at each side is seated, as shown in Fig. 32, the platen-frame cannot be detached from the carriage, because the diameter of each of said heads is greater than the slot of the open bearing 160; but when the heads 158 are pressed inwardly, as shown in Fig. 33, the pintles 160^a may be lifted out from the open bearings and the platen-frame thus detached. By these means platen-frames of different sizes may be readily substituted one for another, or the platen-frame may be readily removed for the purpose of repairing or adjusting any of the parts connected thereto or which operate therebelow.

The platen-frame 126 carries a platen 161, which is provided with the usual finger-wheel 162 at the left-hand end thereof, the platen being adapted to rotate in suitable bearings in the platen-frame. Coöoperating with the platen 161 is a paper-feed roller 163, the shaft of which rests in open-slot bearings in the arms 166, one being provided at each end of the shaft. These arms or links 166 are pivoted to a cross-bar 167 of the platen-frame, and to each arm is connected one end of a coiled spring 169, that surrounds the cross-bar 167. The opposite end 170 of each spring is connected to means (not shown) contained within a housing 171 and by which an adjustment of the tension of each spring is afforded. The arm 166, which sup-

ports the left-hand end of the feed-roller, has rigidly connected thereto a forwardly-extending arm 178, which is fashioned into a finger-key 179 at its forward end. By depressing the finger key or piece 179 the paper-feed roller 163 will be forced out of contact with the platen or the paper thereon, and the paper may be easily adjusted to any desired position on the platen. Each of the arms 166 supports a spring-arm 180, Fig. 30, and the lower ends of these arms are connected by a paper-blade 181, which extends substantially throughout the length of the platen and normally presses thereagainst. This paper-blade may be adjusted with relation to the platen by screws 182, which extend through elongated slots in the spring-arms 180 to secure them in place. The paper-blade being connected to the feed-roller-carrying arms, it will be understood that a downward movement of the finger-key 179 operates to move both the feed-roller and the paper-blade away from the platen, in order that the paper may be freely introduced and adjusted on the platen.

Coöperating with the peripheral teeth 205 on the feed-wheel is a detent or pressure-roller 216, Figs. 28 and 29, which is mounted in bearings upon a spring 217, that is secured to the platen-frame at 218. A line-spacing pawl 219 coöperates with the teeth 206 on the side of the wheel and is actuated by a rock-shaft 220, that turns in bearings 221 on the platen-frame. The forward end of the rock-shaft has secured thereto a finger-piece 222, by which the rock-shaft may be turned to actuate the line-spacing pawl 219, and thus effect a line-feed movement of the platen, as common heretofore in Yost machines.

Various features herein shown and described which relate to the type action constitute no part of my invention, but are the invention of Arthur W. Smith. In this connection it should be understood that instead of the type action shown and described the ordinary Yost or any suitable type action may be employed. It should likewise be understood that various features of the invention may be used in different characters of type-writing machines from that shown, and that to this end numerous changes may be made without departing from the spirit of my invention.

Certain of the features herein shown and described are claimed in Patents Nos. 720,762 and 720,763, issued February 17, 1903, on applications divided out of this case.

What I claim as new, and desire to secure by Letters Patent, is—

1. In a type-writing machine, the combination of a carriage, a feed-rack carried by said carriage, a pinion which engages said rack, a vertically-disposed shaft to which said pinion is fixed, a feed-wheel operatively

- connected to said shaft, a feed-dog, a carriage-release key, and two clutches interposed between the feed-pinion and feed-wheel, one clutch being disengaged by the 5 release-key and the other permitting a movement of the carriage from left to right without turning the feed-wheel, but turning the feed-wheel when the carriage moves from right to left.
- 10 2. In a type-writing machine, the combination of a carriage having a feed-rack, a pinion which engages said rack, a vertical shaft to which said pinion is fixed, a feed-wheel operatively connected to said shaft, a 15 dog for engaging said feed-wheel, two clutches interposed between the feed-pinion and feed-wheel, and hand-operated means for moving said vertical shaft in a longitudinal direction to disengage one of said clutches.
- 20 3. In a type-writing machine, the combination of a carriage having a feed-rack, a shaft carrying a pinion engaging with said rack and carrying also a clutch member, a concentric shaft carrying the other member 25 97 of said clutch and also a feed-wheel, a toothed wheel secured to said concentric shaft, a pawl secured to said clutch member 97 and engaging said toothed wheel, and means on the carriage for moving the pinion shaft endwise and disengaging said clutch members.
- 30 4. In a type-writing machine, the combination of a shaft having a feed-wheel, a clutch member 90 secured to said shaft, a clutch member 97 connected to said clutch member 90, a shaft 102 having a clutch member 100 engaging the clutch member 97, a pinion on said shaft 102, a carriage having a feed-rack engaging said pinion, and means 35 for separating the clutch-sections 100 and 97.
- 40 5. In a type-writing machine, the combination of a shaft having a feed-wheel, a toothed clutch member 90 secured on said shaft, clutch member 97 surrounding said shaft and carrying a pawl to engage said toothed clutch 90, a shaft 102 having a clutch member 100 to engage the clutch member 97, a spring for maintaining the 45 clutches 100 and 97 normally in engagement, a pinion on the shaft 102, a carriage having a rack in engagement with said pinion, and means on said carriage for disengaging the clutch members 100 and 97 against the tension of said spring.
- 50 6. In a type-writing machine, the combination of a shaft having a feed-wheel, a clutch member 90 secured thereto, a loose clutch member 97 surrounding said shaft and having a pawl which engages the clutch 55 member 90, a shaft 102 having a clutching member 100 that engages and turns the clutch member 97, and through the clutch members 95 and 90 the said feed-wheel shaft, a spring surrounding the shaft 102, a housing attached to the clutch member 97 and resist-

ing one end of said spring, which spring acts to hold the clutch members 100 and 97 normally in engagement and rotates therewith and with the housing during such engagement, a pinion on said shaft 102, a carriage 7c having a feed-rack in engagement with said pinion, and means for disengaging the clutch members 100 and 97.

7.. In a type-writing machine, the combination of a carriage having a feed-rack, a tubular shaft 102 having a pinion to engage said rack and having a clutch member 100, a tubular shaft 88 within the shaft 102 and having a feed-wheel 86 and a clutch member 90, a loose clutch member 97 between the 80 clutch members 100 and 90 and connected to both, a spring surrounding the shaft 102, a housing for said spring attached to the clutch member 97, and means on the carriage for disconnecting the clutch members 100 and 97. 85

8. In a type-writing machine, the combination of a carriage having a feed-rack 108, a feed-pinion 106 which engages said rack, a shaft to which said pinion is fixed, a feed-wheel operatively connected to said shaft, 90 roller-bearings for the carriage, a separator for said rollers provided with a rack 112, a pinion 111 engaging said rack 112, a spur-gear 110 for driving said pinion 111 and a pinion 107 on said shaft for turning said spur-gear 110. 95

9. In a type-writing machine, the combination of a carriage, a feed-rack carried by said carriage, a feed-pinion which engages said rack, a shaft to which said pinion is fixed, a feed-wheel operatively connected to said shaft, a dog-rocker, feed-dogs carried by said rocker, an antifriction-roller separator, and independent gear connections between said pinion-shaft and separator. 100 105

10. In a type-writing machine, the combination of a carriage, a feed-rack carried by said carriage, a feed-pinion which engages said rack, a vertically-disposed shaft to which said pinion is fixed, a horizontally-disposed feed-wheel with circumferential teeth operatively connected to said shaft, a horizontally-disposed dog-rocker, feed-dogs carried by said rocker, an antifriction-roller separator and independent gear connections between vertically-disposed shaft and the separator. 110 115

11. In a type-writing machine, the combination of a carriage, a feed-rack carried by said carriage, a feed-pinion which engages 120 said rack, a vertically-disposed shaft to which said pinion is fixed, a feed-wheel operatively connected to said shaft, a dog-rocker, feed-dogs carried by said rocker, an antifriction-roller separator, a rack carried thereby, a second separator-pinion fixed to the vertically-disposed shaft and operative tooth-gear connections between said separator-pinion and the rack on the separator. 125

12. In a type-writing machine, the combi- 130

uation of a carriage, a feed-rack carried by said carriage, a feed-pinion which engages said rack, a vertically-disposed shaft to which said pinion is fixed, a horizontally-disposed feed-wheel with circumferential teeth operatively connected to said shaft, a horizontally-disposed dog-rocker, feed-dogs carried by said rocker, an antifriction-roller separator, a rack carried thereby, a second separator-pinion fixed to the vertically-disposed shaft, and operative tooth-gear connections between said separator-pinion and the rack on the separator.

13. In a type-writing machine, the combination of a carriage, a rack carried by said carriage, a feed-pinion meshing with said rack, an escapement-wheel operatively connected to the feed-pinion, to afford a step-by-step feed of the carriage, coöperating feed-dogs, a carriage-release key and two clutches interposed between the feed-pinion and escapement-wheel.

14. In a type-writing machine, the combination of a carriage, a rack carried by said carriage, a feed-pinion meshing with said rack, a feed-wheel operatively connected to the feed-pinion, a carriage-release key and two clutches interposed between the feed-pinion and feed-wheel, one of said clutches being disengageable by the said release-key and the other automatically disengageable during the backward movement of the carriage.

15. In a type-writing machine, the combination of a carriage, a rack carried by said carriage, a feed-pinion meshing with said rack, a feed-wheel operatively connected to the feed-pinion, a carriage-release key and two independently-revoluble clutches interposed between the feed-pinion and feed-wheel, one of said clutches being spring-pressed and disengageable by the said release-key and the other automatically disengageable during the backward movement of the carriage.

16. In a type-writing machine, the combination of a carriage, a rack carried by said carriage, a feed-pinion meshing with said rack, a hollow shaft upon which said feed-pinion is mounted, a spring-pressed clutch-section carried by said shaft, a feed-shaft contained within said hollow shaft, a feed-wheel secured to said feed-shaft and clutching elements interposed between the spring-pressed clutch and the feed-wheel.

17. In a type-writing machine, the combination of a carriage, a feed-rack carried by the carriage, a feed-pinion which engages said rack, a hollow shaft to which said pinion is fixed, a longitudinally-movable and oscillatory line-lock shaft which extends through said hollow shaft but is movable independently thereof, and line-locking instrumentalities which coöperate with said line-lock shaft.

18. In a type-writing machine, the combination of a carriage, a feed-rack carried by the carriage, a feed-pinion which engages said feed-rack, a hollow shaft to which said feed-pinion is fixed, a longitudinally-movable and oscillatory line-lock shaft which extends through said hollow shaft but is movable independently thereof, a line-lock abutment carried by said line-lock shaft, a coöperating abutment carried by the carriage, and hand-operated means for moving said line-lock shaft in a longitudinal direction to permit said abutments to pass one another. 70

19. In a type-writing machine, the combination with the printing and escapement mechanisms, of a universal ring, a stem extending downwardly therefrom and having a head or catch, a horizontal lever normally out of the path of said head or catch and adapted to be swung thereover, a vertically-arranged and longitudinally-movable and oscillatory shaft having an arm to vibrate said lever, a line-locking abutment attached to the upper end of said shaft, a coöperating abutment on the paper-carriage, whereby the shaft is rocked and the stem and universal ring may be locked against upward movement, and key mechanism for raising said shaft and its connected abutment so that the abutment on the carriage may pass under 90 and by the abutment on the shaft and enable the shaft and its connected lever to be restored to the normal position and the stem and universal ring to be released, so as to permit a further operation of the printing and escapement mechanisms. 95

20. In a type-writing machine, the combination of a carriage, a line-lock abutment carried thereby, a horizontally-disposed carriage-feed-wheel, a vertical oscillatory and longitudinally-movable line-lock shaft, a line-lock abutment carried thereby, an arm secured to said shaft, a line-lock lever operatively connected to said arm, a universal ring, a depending stem connected to said 110 ring, a horizontal dog-rocker connected directly to said depending stem and the feed-dogs on which coöperate with the feed-wheel, and a locking head or catch carried by said stem and with which the locking-lever is 115 adapted to engage to prevent a movement of the universal ring and the dog-rocker.

21. In a type-writing machine, the combination of a carriage, a feed-rack carried by the carriage, a feed-pinion which engages said 120 feed-rack, a hollow shaft to which said feed-pinion is fixed, a line-lock shaft which extends through said hollow shaft, and line-locking instrumentalities which coöperate with said line-lock shaft.

22. In a type-writing machine, the combination of a carriage, a feed-rack carried by the carriage, a feed-pinion which engages said feed-rack, a hollow shaft to which said feed-pinion is fixed, a spring-restored longitudi- 130

- nally-movable and oscillating line-lock shaft which extends through said hollow shaft but is movable independently thereof, a line-lock abutment carried by said line-lock shaft, a co-
5 operating abutment carried by the carriage, locking instrumentalities which are thrown into locking engagement when the two abutments contact and hand-operated means for moving the line-lock shaft longitudinally to
10 move one of the abutments out of the path of the other.
23. In a type-writing machine, the combination of a carriage, a locking-lever controlled by the carriage, a universal ring, a
15 single locking-arm operatively connected to said ring and with which the locking-lever engages, a space-key and means operatively connected to said space-key for actuating the lock-arm to actuate the carriage-feed mechanism.
24. In a type-writing machine, the combination of a carriage, a locking-lever controlled by the carriage, a universal ring, a single locking-arm operatively connected to
25 said ring and with which the locking-lever engages, a feed-dog rocker operatively connected to the locking-arm, a space-key, and means operatively connected to said space-key for actuating the locking-arm to move
30 the dog-rocker.
25. In a type-writing machine, the combination of type-bars arranged in a circle, drivers and guide-links pivoted directly to said type-bars, a universal ring with which said
35 guide-links contact and which is moved by said guide-links, a carriage, and escapement mechanism therefor controlled by said universal ring.
26. In a type-writing machine, the combination of type-bars arranged in a circle, drivers and guide-links therefor, a universal ring adapted to be moved by said guide-links, a
40 depending stem connected to said universal ring and movable with and independently thereof, a dog-holder connected to said stem, escapement devices connected to a paper-carriage and controlled by the movements of
- 50 said stem, a space-key, and means for moving said stem and dog-holder independently of said universal ring.
27. In a type-writing machine, the combination of a carriage, a platen-frame carried thereby, and spring-pressed pivot-plungers which lock the platen-frame to the carriage and on which the platen-frame may be 55 turned.
28. In a type-writing machine, the combination of a carriage, a swinging platen-frame carried thereby, and spring-pressed plungers which have cylindrical locking-heads that 60 lock the platen-frame to the carriage but permit the frame to swing independently thereof, said locking-heads being movable to permit the detachment of the platen-frame.
29. In a type-writing machine, the combination of a carriage, recessed open-mouth bearings carried thereby, a swinging platen-frame, pintles carried by said frame and seated in said open-mouth bearings, spring-pressed plungers having locking-heads that 65 are seated in the recesses in said bearings and lock the platen-frame to the carriage but which permit the frame to swing independently thereof, said heads being movable to permit the detachment of the platen-frame 70 from the carriage.
30. In a type-writing machine, the combination of the frame, a carriage comprising two sections, viz: a carrying-section or base connected with the frame, and a paper-holding section, and mechanism for detachably connecting said two sections of the carriage, said mechanism comprising alining spring-pressed bolts mounted on one of the carriage-sections and loosely engaged with the other 75 carriage-section.
